UNITED STATES PATENT OFFICE.

FRANKLIN S. NIXON, OF PHILLIPSBURG, NEW JERSEY.

CEMENT VAULT.

1,021,623.

Specification of Letters Patent. Patented Mar. 26, 1912.

Application filed May 11, 1911. Serial No. 626,453.

To all whom it may concern:

Be it known that I, FRANKLIN S. NIXON, a citizen of the United States, residing at Phillipsburg, in the county of Warren and State of New Jersey, have invented certain new and useful Improvements in Cement Vaults, of which the following is a specification, reference being had therein to the accompanying drawing.

10 This invention relates to that class of devices for inclosing coffins which are termed burial vaults.

The invention has for its object to provide an improved burial vault of this kind which 15 will be thoroughly air and water proof.

The invention further has for its object to provide a burial vault of this kind which has effective means for supporting the coffin therein and also to enable the vault to 20 be lowered into a grave.

Referring to the accompanying drawings:—Figure 1 is a side view in longitudinal section of a burial vault constructed in accordance with this invention. Fig. 2 is a 25 cross section of the vault. Fig. 3 is a detail view in perspective of means mounted in the bottom of the vault employed for supporting the coffin therein.

The burial vault constructed in accordance with this invention consists of a receptacle 1 adapted to contain a coffin and formed of cement, preferably the best Portland cement. The rim of the casket is formed with a vertical flange 2 on the inner 35 side of the flat portion 3 of the rim, thereby forming a shoulder, the flat portion of the rim being provided with a concave groove 4. A cover 5 is provided also formed of cement having an inner shoulder 40 6 adapted to be seated over the flange 2, the rim of the cover being seated upon the flat portion 3 of the rim of the vault, and having a bead 7 which fits into the groove 4. Located in the bottom of the vault adjacent 45 to each end thereof is a support for a coffin, each of said supports consisting of a transverse metallic rod 8 having depending ends 9 each terminating in a ring 10, through which a rod 11, preferably secured thereto 50 by welding, projects. The rod 8 also has a depending portion 12 terminating in an eye

13 through which extends a short rod 14 similar to the rods 11, and also preferably welded to the eye 13. The depending end portions of the rod 8 and the central depending portion thereof with the rods 11 and 14 are embedded in the sides and bottom of the vault, as shown in Fig. 2, when the vault is formed, with the rod 8 slightly elevated above the bottom of the vault. 55 Each of the rods 8 is formed adjacent to its depending end with a curved portion 15 which serves not only as a means for engagement by a hook connected with the rope for lowering the vault into a grave but also 60 the two curved members 15 which are located on each side of the coffin serve to steady the coffin in place. It will be seen that by means of the rods 8 that a firm, slightly elevated support is provided for a coffin 65 which supports the coffin slightly above the bottom of the vault. The cover 5 is provided adjacent to each end with a pair of metallic loops or rings 16 having their ends embedded in the cement, said rings serving 70 for the attachment of ropes for lowering the cover of the vault into place upon the receptacle. The vault is sealed by means of a suitable drying cement which is located 75 in the groove 4. 80

It will be seen that by means of this invention a thoroughly air and water proof vault is provided having means for lowering the vault into a grave and supporting the coffin placed in the vault. 85

What I claim is:—

A cement burial vault consisting of a cement receptacle having transverse rods slightly elevated formed with depending end projections, and a central depending 90 projection above the bottom of the receptacle, and curved raised portions adjacent to said depending end projections, said depending projections each having an anchoring bar embedded therewith in the receptacle. 95

In testimony whereof I hereunto affix my signature in presence of two witnesses.

FRANKLIN S. NIXON.
